(57) **CLAIM**

The ornamental design for a beverage temperature control attachment hose, as shown and described.

DESCRIPTION

FIG. 1 is a right elevation view of a beverage temperature control attachment hose showing my new design, the opposite side being a mirror image of the shown;

FIG. 2 is a front elevation view thereof;

FIG. 3 is a rear elevation view thereof;

FIG. 4 is a top plan elevation view thereof;

FIG. 5 is a bottom plan view thereof;

FIG. 6 is an isometric view thereof; and,

FIG. 7 is an in-use view thereof.

The broken lines in the drawings depict environmental subject matter only and form no part of the claimed design.
